CAP CLOSURE

David B. Ronzone, Brooklyn, N. Y., assignor to
 Vacuum Packing Corporation, Salem, N. J., a
 corporation of Delaware

Application June 2, 1931. Serial No. 541,601

1 Claim. (Cl. 215—40)

The present invention relates to cap closures and particularly to cap closures for closing jars.

It is an object of the invention to provide a cap closure capable of closing and sealing a jar 5 or container against the admission thereto of air.

A further object is to provide such a closure which can be easily and quickly removed with an ordinary knife without destroying or damaging the closure.

A still further object is to provide such a closure in combination with a container each of which cooperates with a rubber or similar washer in such a way as to permit the manual re-closing of the container to form a perfect seal against the admission of air, the position of the parts after re-closing being the same, or substantially the same, as in the original closing and sealing, the parts being so arranged that 20 there is a distinct tendency for the closure to maintain itself in sealing position but being always removable by the simplest kind of convenient implement, such as an ordinary knife.

Other objects and advantages of the invention will appear from the following description taken in connection with the accompanying drawing which illustrates a preferred embodiment of the invention and in which

Figure 1 is a top plan view of a container and closure constructed in accordance with the present invention;

Figure 2 is a side elevation thereof partly in section on the line 2—2 of Figure 1;

Figure 3 is a fragmentary vertical sectional view on a larger scale and taken on the line 3—3 of Figure 1;

Figure 4 is a view similar to Figure 3 and illustrating a modified form of cap;

Figure 5 is a fragmentary sectional view of 40 the sealing washer.

Referring in detail to the drawing, the container 11 is provided with an annular sealing flange 12 about its mouth. The flange 12 may be exteriorly spherically or similarly curved as 45 shown in Figures 2, 3 and 4 so that the over-all diameter of the flange 12 increases, going downwardly from the top as viewed in Figure 2, to a maximum and thereafter decreases from that maximum before reaching the radially extending flange 14 which is adapted to be engaged by a knife or similar readily convenient implement for the purpose of removing the closure.

A cap 15 is provided for the container and in the preferred form the cap is made of relatively thin metal and is provided with a down-

wardly extending flange 16, the bottom of which is rolled outwardly into a bead 18, the whole of which is thereafter bent inwardly to provide for the reception and support of a sealing washer 20 which is preferably of rubber and is normally 60 cylindrical or substantially cylindrical internally and externally, its normal internal diameter, undeformed, being less than the maximum external diameter of the sealing flange 12 of the container.

As a result of this structure, when the cap closure is placed upon the container, as shown in Figure 2, with the top surface of the cap in contact with the upper edge of the flange 12, and the bead 18 somewhat spaced from the radial flange 14 of the container, to permit insertion of 70 a knife or similar convenient implement between said flange and the bead, the deformable washer has the shape shown in Figures 2, 3 or 4, being compressed to a maximum degree at some point 75 intermediate its upper and lower edges and its internal diameter when so compressed and deformed being greatest intermediate its upper and lower edges and being least at either its upper or lower edges or at both where the parts are so formed as to make the uppermost and lowermost 80 internal diameters equal.

As a result of the foregoing construction, the closure tends to remain in sealing and closing position not only when forming a vacuum seal as 85 applied, for example, to the closure by the packer, but also when the purchaser of the container has broken the vacuum seal, used part of the contents and has returned the closure to the closing position of Figure 2 by manual pressure.

It will be observed that in each case the removal of the closure is necessarily accompanied by a compression of the sealing washer and that due to the construction described, the closure may be removed as often as desired and reapplied to 90 the container as often as desired to form an effective and airtight seal, all without in any way deforming or otherwise damaging the cap closure itself.

While it is preferred that the depending flange 100 of the closure be cylindrical, it is obvious that it need not necessarily be so in order to practice the invention. For example, it may be slightly conical as shown in Figure 3, the essential feature being that arrangement of parts that causes removal of 105 the cap to be accompanied by a compression of a part of the sealing washer other than that part of it which is always under compression when the cap is in the closing position, there being always a compression of said washer due to a complete 110

peripheral internal surface engagement with the flange 12 and a complete peripheral external surface engagement with the inside of the cap flange 16.

5 What is claimed is:

In combination, a container and a closure therefor having an annular flange extending inwardly near its bottom, a resilient sealing washer held in said closure by said flange, the bottom of 10 said flange being rolled outwardly to form a bead substantially in alignment with the closure top

edge, said container having an annular sealing flange curved in two directions at right angles to each other and variably deforming said washer, by compressing it against said annular flange and thereby variably reducing its thickness and bringing its inner face into contacting conformation with the two-directional curve of said annular sealing flange, said container having a radially extending fulcrum flange below, adjacent and substantially in alignment with the closure bead.
